DETACHABLE HANDLE FOR A DECANTER OR SIMILAR ARTICLE

Daniel L. Killigrew, Jr., Corning, N.Y., assignor to Corning Glass Works, Corning, N.Y.

Filed Apr. 26, 1971, Ser. No. 137,724

Term of patent 14 years

Int. Cl. D7—99

U.S. Cl. D44—21

Fig. 3

Fig. 4

Fig. 5

FIG. 1 is a side elevational view of a detachable handle for a decanter or similar article showing my new design.

FIG. 2 is a top plan view taken generally on line 2—2 of FIG. 1.

FIG. 3 is a bottom plan view taken generally on line 3—3 of FIG. 1.

FIG. 4 is an end elevational view taken generally on line 4—4 of FIG. 1.

FIG. 5 is an enlarged cross-sectional view taken on line 5—5 of FIG. 1.

I claim:

The ornamental design for a detachable handle for a decanter or similar article, as shown.
